(57) **CLAIM**

The ornamental design for a transcranial magnetic stimulation device, as shown and described.

DESCRIPTION

FIG. 1 is a front view of a transcranial magnetic stimulation device;

FIG. 2 is a back view of a transcranial magnetic stimulation device;

FIG. 3 is a first side view of a transcranial magnetic stimulation device;

FIG. 4 is a second side view of a transcranial magnetic stimulation device; and,

FIG. 5 is a top plan view of a transcranial magnetic stimulation device.

The broken line shown in FIG. 1 is included for the purpose of illustrating portion of the transcranial magnetic stimulation device and forms no part of the claimed design.

1 Claim, 5 Drawing Sheets

Related U.S. Application Data

said application No. 29/770,198 is a continuation-in-part of application No. 17/065,412, filed on Oct. 7, 2020, said application No. 29/770,199 is a continuation-in-part of application No. 17/065,412, filed on Oct. 7, 2020, which is a continuation-in-part of application No. 16/867,130, filed on May 5, 2020, now Pat. No. 11,517,760, said application No. 17/308,426 is a continuation-in-part of application No. 16/867,130, filed on May 5, 2020.
